UNITED STATES PATENT OFFICE.

ROBERT MIEHLE, OF CHICAGO, ILLINOIS, ASSIGNOR TO CONTINENTAL & COMMERCIAL TRUST & SAVINGS BANK, TRUSTEE, OF CHICAGO, ILLINOIS.

CUSHIONING DEVICE FOR PRINTING-PRESSES.

1,089,063.

Specification of Letters Patent. Patented Mar. 3, 1914.

Application filed September 10, 1912. Serial No. 719,561.

To all whom it may concern:

Be it known that I, ROBERT MIEHLE, a citizen of the United States, and a resident of Chicago, in the county of Cook and State of Illinois, have invented certain new and useful Improvements in Cushioning Devices for Printing-Presses; and I do hereby declare that the following is a full, clear, and exact description thereof, reference being had to the accompanying drawings, and to the letters of reference marked thereon, which form a part of this specification.

This invention relates to air-cushioning means for printing presses, of the kind in which the momentum of the reciprocating bed of the press is checked near the end of its stroke by means of an air cushion and the energy stored up in overcoming the momentum of the bed is utilized for starting it in the opposite direction, and more especially to that class of such devices embracing a cushioning cylinder and piston, and in which the amount of air compressed in the cushioning cylinder is controlled automatically through the medium of a valve on the cylinder and a governor acting to control the operation of said valve. A mechanism of this same general character is illustrated in my prior Letters Patent No. 337,853, issued March 16, 1886, and No. 989,384, issued April 11, 1911.

The object of the present invention is to improve and simplify the construction of the devices of the character shown in said Letters Patent in several respects, as will be hereinafter set forth, and the invention consists in the matters hereinafter described and pointed out in the appended claims.

In the accompanying drawings illustrating my invention, Figure 1 is a view in end elevation of a printing press equipped with an air cushioning device embodying my invention; Fig. 2, a fragmentary, longitudinal, detail section, of a printing press, showing the air cushioning device and valve controlling mechanism of the cylinders thereof; Fig. 3, a detail plan view of the governor and its associated parts; Fig. 4, a detail view, as seen from beneath, of the inner end of one of the cushioning cylinders; Fig. 5, a detail view of a casing which carries the air outlet valve of the cylinder, when removed from said cylinder; Fig. 6, a detail

face view of the rotative valve member; and Fig. 7, a view in side elevation of said valve member.

The printing press illustrated is one of a well known type of flat-bed presses, comprising a rotative impression cylinder 5, a reciprocating type-bed 6 and a main frame in which said parts are supported, said frame embracing longitudinal side plates 7, 7. The reciprocating bed 6 is given endwise reciprocatory movement through the medium of a well known form of actuating device, embracing a frame 8 which is attached to and depends from the bottom of the bed and extends longitudinally thereof; upwardly and downwardly facing rack bars 8^a, 8^a on said frame, a gear wheel 9 which has vertical movement to bring the same into meshing engagement with either of the rack bars 8^a, 8^a; a shaft 10 on which said gear wheel 9 is mounted and a crank arm 11 on said shaft 10, said crank arm being provided with a crank pin 11^a adapted to act in vertical slots that are formed between the vertical end-members 8^b, 8^b of the frame 8 and oscillating members 8^c arranged inside of and parallel with said end-members. The mechanism shown also includes a horizontal rotative shaft 12 carrying a cam 13 which is engaged by a rock-arm 14, through which vertical movement is given to the gear wheel 9, as common in printing presses of this type. The rock arm 14 is provided with a cam roller 14^a engaging the eccentrically formed path of the cam 13, and thereby giving the adjacent extremity of the arm 14 a vertical reciprocatory movement. The rock arm 14 is fulcrumed at its upper end with a bearing shaft 14^b mounted in a horizontal position upon the frame. Between the extremities of the rock arm 14 and adjacent to the fulcrum points is rotatively mounted the shaft 10, which receives a similar and reduced vertically reciprocating movement due to the lever action of the rock arm 14.

The air cushioning cylinders 15, 15 are attached to the frame of the press near each end thereof. Two pairs of such cylinders are shown; the cylinders constituting each pair being located at opposite sides of the central, longitudinal line of the press. Associated with each cylinder 15 is a piston 16,

which is secured to a horizontal, longitudinally extending piston rod 17. Said piston rod 17 carries at its opposite ends the two pistons belonging to one pair of cylinders, and is rigidly attached to the bed 6 by means of a rigid hanger or bracket 18, secured to and depending from said bed, and to which said piston rod is centrally attached. The arrangement of the cylinders and pistons is such that as the bed nears the end of its stroke in either direction, one of the pistons will enter its cushioning cylinder to compress a quantity of air therein acting to afford resistance to the momentum of the bed, the air thus compressed expanding and exerting pressure upon the piston upon the reversal of the movement of the bed, to aid in overcoming the inertia of the same.

Each of the cylinders 15 is provided with an air outlet valve, indicated as a whole by 20, mounted on the closed outer end of the cylinder, and with a plurality of air inlet valves, indicated as a whole by 21, located in the bottom wall of the cylinder adjacent to its outer end. The outlet valve 20 has the form of an oscillatory disk valve, while the inlet valves 21 have the form of inwardly opening check valves.

Now, referring to the details of construction illustrated in each air outlet valve 20, the same is constructed as follows: The movable member of the valve, as clearly seen in Figs. 6 and 7, consists of a disk 25 provided with a plurality of annularly arranged ports or apertures 26 having radial side margins. Said valve disk is attached to one end of a valve stem 27. To the opposite end of said stem is secured an actuating arm 28 provided at its outer end with a slotted or forked extremity 29. The said valve disk is preferably provided with a marginal stiffening or strengthening flange 25^a, and the ports 26 extend outwardly to the inner face of said flange. The fixed member of the said valve consists of a hollow casing 30 which is secured by bolts to the end wall or head of the cylinder, and consists of parallel inner and outer walls 30^a and 30^b connected with each other at their side and top margins by an integral connecting wall 30^c. Said casing is vertically elongated and its upper part is applied over or covers a circular aperture 15^a formed in the head of the cylinder, as shown at the left-hand side of Fig. 2 and in dotted lines in Fig. 4. In the inner wall 30^a of the said casing, is formed a plurality of annularly arranged ports 33 corresponding with the ports 26 of the valve disk 25. Said casing is so applied to the end wall of the cylinder that the upper part of the inner wall 30^a, containing the ports 33, covers or closes the circular aperture 15^a and the portion of said inner wall in which said ports 33 are formed, constitutes a seat, which faces inwardly or

toward the interior of the cylinder, for the valve disk 25. A bearing for the valve stem 27 is provided in said casing 30 by means of a hub 34 made integral with and extending between the inner and outer walls 30^a and 30^b of said casing (see Fig. 4); the actuating arm 28 being located at the outer face of said casing and the valve disk being located in contact with the valve seat formed on the inner face of said casing and within the aperture 15^a, as seen in Fig. 2 and in dotted lines in Fig. 4. The valve disk 25 is given oscillatory motion for opening or closing the air outlet ports 33, the said ports being opened by turning the disk so as to bring the ports 26 into position to register with said ports 33. By providing the cylinder with an inwardly facing valve seat and locating the valve disk inside of the wall on which said valve seat is formed, said valve disk is held or pressed by the air pressure in the cylinder against its seat, so that the air pressure tends to maintain a tight joint between the valve disk and its said seat. The air passing from the cylinder through the ports 33 enters the interior of the casing 30 and is delivered in a downward direction through the open lower end of said casing; this construction being employed to prevent the delivery of air in a direction which would be troublesome or objectionable in the operation of the machine.

The air outlet valves 20, associated with the four cushioning cylinders, are actuated through the medium of two horizontal, longitudinally arranged rock-shafts 35, 35. Each rock-shaft 35 extends at the sides of the two cylinders which are located in line with each other at opposite ends of the machine, constituting one pair of cylinders, and said rock-shaft has operative connection at its ends with the valve disks 25, 25 belonging to such cylinders. At its end adjacent to each valve, said rock-shaft 35 is mounted in a bracket arm 36 made integral with and extending laterally from the casing 30 (Figs. 4 and 5). One of said rock-shafts 35 has an intermediate bearing in a bracket arm 37 (Figs. 1 and 2) on the machine frame. For transmitting movement from each rock-shaft to each valve disk 25, said rock-shaft is provided at each end, outside of the bracket 36, with a rigidly attached crank arm 38, provided with a stud or pin 38^a which engages the forked extremity 29 of the crank arm 38, so that the valve disk 25 will be turned or oscillated to a degree corresponding with the rocking movement imparted to the said shaft. The two rock-shafts 35, 35, severally associated with the two pairs of cylinders at opposite sides of the machine, are so connected with each other as to have corresponding degree of oscillatory movement. The means shown for this purpose consists of depending arms 39, 130

39 rigidly secured to the rock-shafts and connected with each other by a horizontal connecting rod 40.

As a part of the devices by which the several air outlet valves are actuated, said valves are held normally in their open position by spring actuated means, which, in the machine illustrated, operate through the medium of the said connecting rod 40 and the rock-shafts 35, 35. As shown, a contractive, coiled spring 41 is attached at one end to said rod 40 and at its opposite end to the machine frame, said spring tending to move the said rod endwise and to rotate the rock-shafts 35 in one direction. A stop pin 42 on the bracket 37 serves, by its contact with the arm 39 on one of said rock-shafts, to limit the turning movement of both rock-shafts under the action of said spring 41, so that the valve disks 25 are held normally in position in which the several valve ports 33 are open or uncovered.

Now, referring to the devices employed for giving movement to the several valve disks 25, in order to close the outlet valves and prevent the escape of air from the cylinders, means are provided as follows: To one of the rock-shafts 35 is secured a rigid arm 45 which extends downwardly and laterally from said rock-shaft. To the lower end of said arm 45 is pivotally connected a rod 46 which extends downward toward the base of the machine frame. A bracket 47 is attached to the base of the machine frame and is provided with two arms 47^a and 47^b. Secured at its ends in said arms, and extending between the same (Figs. 1 and 3), is a fixed shaft 48 arranged adjacent to and parallel with the shaft 12, which extends across the machine frame and carries the cam 13, by which vertical movement is given to the gear wheel 9, as hereinbefore described. On said shaft 48 is mounted a sleeve 49 which is adapted to slide endwise, and also has oscillatory or rocking movement on said shaft. Attached to said sleeve 49 is a rigid arm 50 which extends from said sleeve laterally over the shaft 12. Mounted on said shaft 12 is a cam 51 provided with two oppositely arranged, tapered cam projections 52, 52 adapted to act upon the said arm 50 in a manner to give swinging or oscillatory motion to said arm. As preferably constructed, said arm 50 is provided with an anti-friction roller 50^a arranged in a position to act upon the said cam. The free end of said arm 50 is loosely connected or engaged with the lower end of the upright rod 46 in such a manner that the rising and falling movement imparted to said arm 50 by the action of the cam 51 is transmitted to the lower end of the arm 45 on the rock-shaft 35 and gives oscillatory movement to said rock-shaft. Mounted on the fixed shaft 48 is a centrifugal-weight governor which is driven

or rotated from the shaft 12, and which acts to give endwise shifting movement to the sleeve 49 on said shaft, in such a manner as to move or shift the arm 50, on said sleeve, in a direction endwise of said shaft 12 and 70 the tapered cam 51. As shown, said governor comprises a sleeve 55 adapted to turn on the shaft 48 but having no endwise movement thereon, a second sleeve 56, which has both rotative and endwise shifting movement on said shaft, governor arms 57, 57 pivoted to sleeve 55 and carrying governor weights 58, 58, and links 59 which are pivotally connected with the outer ends of the arms 57 and with the endwise movable 80 sleeve 56. An expansively acting coiled spring 60 surrounds the shaft 48 between the sleeves 55 and 56 and by its endwise action on said sleeve 56, tends to hold the governor weights in their retracted position. 85 The governor, embracing the parts described, is driven or rotated through the medium of a gear pinion 61 on the sleeve 55 and a gear wheel 61^a on the shaft 12. The endwise shifting sleeve 56 of the governor 90 is so connected with the sleeve 49 as to transmit endwise shifting movement to said sleeve while permitting free rotative movement of said sleeve 56 with the governor weights. As shown, said sleeve 56 is provided with a radial flange 56^a which is engaged by an annular, grooved plate 49^a attached to the adjacent flanged end of the said sleeve 49, as seen in Fig. 1.

Referring to the details of construction in 100 the air inlet valves 21, each of the cylinders 15 is shown as provided with three of such valves, having the form of upwardly open check valves, adapted to close by gravity and located adjacent to the inner end of the 105 cylinder in the bottom wall thereof. The three valves illustrated are arranged in a line transverse to the central axis of the cylinder and are located in a horizontal wall 70 extending across the rear end of the cylinder, and made integral with downward extensions of the cylindric wall and head of the cylinder. Each of said valves 21, as more clearly shown in Fig. 2, consists of a ring 63 inserted and secured in a circular 115 aperture in the wall 70 and has an annular valve seat at its upper end, and a movable valve member, consisting of a disk 62 adapted to rest upon said seat and provided with a downwardly extending valve stem 62^a 120 having guiding engagement with a central hub 64 connected by radial arms 64^a with the ring 63. The valve member 62 rests by gravity in its closed position, and is lifted by external air pressure, to admit air to the 125 cylinder, through the partial vacuum produced in the cylinder by the outward movement of the piston in said cylinder.

So far as is concerned the operation of the mechanism described, in the closing of the air 130

outlet valves, the same operates substantially in the same manner as set forth in Patents Nos. 337,853 and 989,384 hereinbefore referred to. That is to say, the cam 51 is rotated in unison with the reciprocating motion of the bed 6 and is, therefore, timed in its movement with relation to the movement of the piston 16, while the speed of the governor weights corresponds with the rate or rapidity of the movement of the bed. When the roller 50^a is engaged by the wider or larger part of the cam, the air outlet valve 20 will be closed early in the inward stroke of the piston, and more air will be confined in the cylinder than occurs in the case when the said roller is at the other or narrower end of said cam. It follows, that the position of said roller 50^a with relation to the length of the cam determines the point in the stroke of the piston at which the air outlet valve closes, when the piston is moving inward in the cylinder. This position of the roller relative to the cam is determined by the speed of rotation of the governor, which corresponds with the speed of travel of the piston, and it follows, that the time of the closing of said outlet valve will be varied according to the speed of the bed of the press. If the bed be moving very slowly and no cushioning effect at all be required, the air outlet valve will remain open during the entire stroke of the piston, thereby avoiding any resistance whatsoever in starting the press. At this time the valve will be held open by its actuating spring and the governor will turn so slowly as to leave the roller, 50^a opposite the smaller part of the cam, which will then give no closing movement to the valve disk 25. When, however, the speed of the press is increased, the governor will come into action to move the roller 50^a lengthwise of the cam to a greater or less extent and the cam will then operate, through the intermediate mechanism described, to close the valve at an earlier or later period in the inward stroke of the piston, according to the rate of speed of the bed, so that the air will be confined in the cylinder at an earlier or later period in the movement of the piston and thereby produce a greater or less cushioning action, according to the rate of movement of the bed. In the outward or return stroke of the piston, the air confined in the cylinder will serve to aid in overcoming the inertia of the bed, but, after the expanding air reaches atmospheric pressure and as soon as the pressure within the cylinder becomes less than atmospheric pressure, the suction produced by the outward movement of the piston will effect the opening of the air inlet valves, permitting the inflow of air to the cylinder, and thereby preventing the formation of a partial vacuum and a consequent retardation in the movement of the bed, which would result if

the air were not freely admitted to the cylinder in the outward stroke of the piston.

In the devices shown in the prior patents referred to, a single valve is provided for both the inflow of air to and the outflow of air from the cushioning cylinder. The use of such a single air valve for each cylinder has this advantage that the valve is opened to relieve the piston from external atmospheric pressure at the same point in its outward stroke that said valve is closed in its inward stroke, and, as the valve may not, in such cases, be opened at exactly the point in the outward stroke of the piston at which the pressure against its two faces is equal, the movement of the piston may be retarded by atmospheric pressure on its outer face. By the construction herein described, wherein separate air-admission valves are provided, the admission of air to the cylinder will be effected independently of the operation of the outlet valve, and the piston will be relieved from external atmospheric pressure at the proper point in the outward movement of said piston regardless of the operation or position of the governor weights.

The employment of rotative disk valves, for controlling the air outlet ports, so arranged that the rotative members or disks thereof bear outward against their valve seats, affords the advantage that the valves are simple in form and durable in structure and will always be kept tight, regardless of wear between the disks and their seats.

The employment of a single longitudinally extending rock-shaft as a means of giving oscillatory movement to the air outlet valves belonging to the two cylinders at opposite ends of the machine, has the advantage of greatly simplifying the construction of the parts and of affording a simple, durable and reliable means of transmitting motion from the controlling or regulating device to the valve members. An important advantage is also gained by the special construction shown and described in the casings which are attached to the cylinders and form the seats for the air outlet valves as well as bearings for the valve stems and outlet passages for the air which escapes from the cylinders.

Another advantage gained by the construction herein set forth, as compared with cushioning devices shown in my said prior patent, is that my present construction avoids the use of air pipes through which the air is delivered in its escape from the cylinders; the presence of such air pipes having the disadvantage that the same act by their frictional resistance to the passage of air therethrough to retard the passage of air from the cylinders, so as to interfere to a greater or less extent with the automatic control of the cushioning action. These disadvantages especially arise in the prior con-

struction referred to because of the unequal lengths of the pipes through which the air passes from the different cylinders, giving an irregularity in the cushioning action of the same. Moreover, where a single valve controls the outlet from the escape pipes leading from two cylinders, it has been found necessary to make both the pipes and valve of unduly large size, in order to give 10 a sufficiently free discharge for the escaping air, and even when made of the largest practicable size, the force or pressure of the escaping air not only has the effect of heating the pipes, but of making an objectionable 15 noise. In the construction of my present invention, the air escapes directly from the cylinders through the outlet valves; it being understood that the hollow casings which cover the outlet ports, are made of sufficiently large size to permit free escape of 20 the air, and serve only to direct the escaping air downwardly and to protect the outlet valves from dust, dirt or ink that might fall upon or become lodged in the said 25 valves.

The feature of construction in each cylinder, by which the same is so formed at its lower part and adjacent to its inner or closed end as to provide a flat, horizontal wall located beyond the path of the piston, which wall is apertured to form an inlet port or ports, and is adapted to receive or support the check valve or valves for said inlet port or ports, has the advantage of affording a 35 simple and economical construction in a horizontally arranged cylinder, by which an upwardly-opening and gravity acting check valve may be located or mounted in such position, and in such relation to the cylindric 40 bore of the cylinder, as to insure the proper and reliable operation of such check valve.

A device of the general character herein described may be variously modified without departure from the spirit of my invention, and I do not, therefore, desire to be limited to the specific details and features of construction illustrated and hereinbefore set forth, except so far as the same may be pointed out in the appended claims as constituting parts of my invention.

I claim as my invention—

1. In a cushioning device for printing presses, the combination of an oscillatory valve having an oscillating operating arm and a speed-governor device for controlling the time of operation of the valve, provided with an oscillating, laterally shifting arm, and means for transmitting movement from said oscillating arm of the speed governor device to the operating arm of the said valve, comprising a rock shaft mounted to turn on an axis parallel to the axis of oscillation of said valve; said rock shaft being provided with two rigidly attached arms, one of which has engagement with the said

operating arm of the valve, and means for transmitting to the other of said arms, the oscillatory movement only of said oscillating arm of the speed-governor device.

2. In a cushioning device for printing 70 presses, the combination with an oscillatory cylinder valve having an oscillating operating arm, of a speed-governor device provided with an oscillating arm which has shifting movement in a plane at right angles 75 to the plane of its oscillatory movement, and means for transmitting oscillatory movement from the oscillating arm of the speed-governor device to the operating arm of the valve, comprising a rock shaft mounted to 80 turn on an axis parallel with the axis of oscillation of the valve; said rock shaft being provided with two rigidly attached arms, one of which has engagement with said valve-operating arm, and a connecting rod 85 loosely connected at one end with the oscillating arm of the speed-governor device and at its opposite end with the other rigid arm on said rock shaft.

3. In a cushioning device for printing 90 presses, the combination with an oscillatory cylinder valve having an oscillating operating arm adapted to turn on a horizontal axis, of a speed-governor device located at a distance below the level of the axis of the valve and 95 provided with a vertically oscillating arm which has horizontal shifting movement, and means for transmitting oscillatory movement from the said oscillating arm of the speed-governor device to the operating 100 arm of the valve, comprising a rock shaft mounted to turn on a horizontal axis parallel with the axis of oscillation of the valve; said rock shaft being provided with a rigidly attached arm having operative connection 105 with said valve operating arm and with a second rigidly attached arm the swinging end of which is located approximately in vertical alinement with the swinging end of the said oscillating arm of the speed-governor device, and an upright connecting rod 110 loosely connected at its lower end with said oscillating arm of the speed-governor device and at its upper end with the swinging end of the second rigid arm of the rock shaft. 115

4. In a cushioning device for printing 120 presses, the combination with two cushioning cylinders located in alinement with each other, said cylinders being provided each with an oscillatory controlling valve having an oscillatory operating arm, turning on a horizontal axis, and a speed governor device located at a distance below the level of the axis of the valve, and provided with a vertically swinging oscillating arm having shifting movement in a horizontal plane, a rock shaft mounted to turn on a horizontal axis parallel with the axis of oscillation of said valves and provided with three rigid arms, 125 two of which have operative connection with 130

the operating arms of said valves, and a connecting rod loosely connected at its lower end with the said oscillating arm of the speed-governor device and at its upper end with the said third arm of the said rock shaft.

In testimony, that I, claim the foregoing

as my invention I affix my signature in the presence of two witnesses, this 2nd day of September A. D. 1912.

ROBERT MIEHLE.
